(57) **CLAIM**

The ornamental design for a leisure suit with convertible pants, as shown and described.

DESCRIPTION

FIG. 1 is a front perspective view of the top portion of the leisure suit with convertible pants of the instant invention; FIG. 2 is a front elevational view of the top portion of the leisure suit with convertible pants; FIG. 3 is a side elevational view of the top portion of the leisure suit with convertible pants; FIG. 4 is a back elevational view of the top portion of the leisure suit with convertible pants; FIG. 5 is a front perspective view of the convertible pants portion of the leisure suit with convertible pants of the instant invention; FIG. 6 is a front elevational view of the convertible pants portion of the leisure suit with convertible pants; FIG. 7 is a left elevational view of the convertible pants portion of the leisure suit with convertible pants; FIG. 8 is a right elevational view of the convertible pants portion of the leisure suit with convertible pants; FIG. 9 is a rear elevational view of the convertible pants portion of the leisure suit with convertible pants; FIG. 10 is a front perspective view of a second embodiment of the front of the convertible pants portion of the leisure suit with convertible pants; and, FIG. 11 is a front perspective view of the convertible pants portion of the first embodiment of the leisure suit with convertible pants with the lower part of the convertible pants removed and illustrated in phantom lines. The broken lines shown surrounding the leg portions is understood to represent stitching. The broken lines showing two extended legs in FIG. 11 is for illustrative purposes only and forms no part of the claimed design.
